UNITED STATES PATENT OFFICE.

EMANUEL AUFIERO, OF BROOKLYN, NEW YORK.

DESIGN FOR A HANDLE FOR HAND-ACTUATED WARNING-SIGNALS.

44,994.

Specification for Design.

Patented Dec. 9, 1913.

Application filed July 15, 1913. Serial No. 779,225. Term of patent 7 years.

To all whom it may concern:

Be it known that I, EMANUEL AUFIERO, a citizen of the United States, residing at Brooklyn, in the county of Kings and State of New York, have invented a new, original, and ornamental Design for a Handle for Hand-Actuated Warning-Signals, of which the following is a specification, reference being had to the accompanying drawing, forming part thereof.

Figure 1 is a side view of the design; Fig. 2 is a rear view of same.

I claim:

The ornamental design for a handle for hand actuated warning signal as shown.

EMANUEL AUFIERO.
